[57] **CLAIM**

The ornamental design for a hard cover gun case, as shown and described.

DESCRIPTION

FIG. 1 is a right side elevational view of a hard cover gun case showing my new design, with the left side elevational view being a mirror image thereof;

FIG. 2 is a top plan view;

FIG. 3 is a left side elevational view, showing the hard cover gun case in an open position;

FIG. 4 is a bottom plan view;

FIG. 5 is a front elevational view;

FIG. 6 is a rear elevational view; and,

FIG. 7 is a cross section taken along lines 7—7 of FIG. 3.
